LEVEL LUFTING JIB CRANE

Ignatius Kay, London, England, assignor to The Wellman Smith Owen Engineering Corporation Limited, London, England, a company of Great Britain

Application March 15, 1944, Serial No. 526,577
In Great Britain March 15, 1943

12 Claims. (Cl. 212—8)

This invention relates to level luffing jib cranes and has for its main object the provision of an improved construction which shall have the generally recognized characteristics of such a crane while being capable of operation at high speed with complete safety.

The characteristics referred to are, briefly, (1) horizontal movement of the load hook when the jib is luffed and (2) a balanced jib. A desirable additional feature, not found in all level luffing cranes but possible to provide in those according to this invention, is (3) substantially constant horizontal velocity of the load hook during luffing of the jib. The horizontal movement of the hook should preferably be due to operation of the luffing gear only, independently of the hoist gear, so that both luffing and hoisting may be effected together when desired.

This invention consists in a level luffing jib crane having a balanced jib the centre of gravity of which moves in a substantially horizontal path during the luffing of the jib and in which the latter is supported from the frame of the crane by links or the equivalent so disposed and dimensioned that the end of the jib remote from the load is constrained to move in a substantially vertical path.

In order that the invention may be clearly understood, there will now be described some practical examples of the improved crane construction and the way in which it has been developed theoretically, reference being made to the accompanying diagrammatic drawings.

In the drawings:

Figs. 1 to 4, inclusive, are line diagrams illustrating stages in the development of the linkage arrangement constituting a main feature of this invention.

Fig. 5 is a diagrammatic side elevation of one form of crane embodying a practical example of this linkage arrangement, the centre of gravity of the jib being at the centre of length of the latter.

Fig. 6 is a similar view of another crane according to the invention in which a different location of the centre of gravity of the jib has necessitated an alteration in the reeving of the ropes, and

Fig. 7 is a similar view of a third form of crane having two separate load hooks which are of different load-carrying capacities and located at different distances from the centre of gravity of the jib.

In each of the Figs. 5 to 7 only the parts essential to the clear understanding of the present invention have been indicated, the main members of the jib being shown in heavy lines and the main members of the frame by double lines. Many of the bracing members and other known constructional details, including means permit-

ting of slewing the crane or traversing it along rails when desired, have not been illustrated as their arrangement or construction will be obvious to those skilled in the art.

5 The manner in which the cranes according to this invention are adapted to operate can best be explained by reference to the diagrams of Figs. 1 to 4.

As a first step and considering Fig. 1, assume 10 that a pivoted jib A, B mounted on a crane frame (not shown) has rigidly affixed thereto at the pivotal point C the upper end of a downwardly extending arm D (equal in length to the tail portion B of the jib extending beyond the pivot C) having its lower end pivoted at E to the forward end of a thrust link F disposed substantially parallel with the tail portion B. If the rear end of the thrust link F be located (as shown) vertically beneath the end of the tail portion B and there pivoted, at G, to the upper end of a radial link H which extends downwardly and forwardly to a fixed pivot I on the crane frame (not shown) vertically beneath the pivotal point C of the jib and is of the same length as the arm D secured to 15 the jib, any angular movement imparted to any member of the system (see the chain-dotted lines) will be exactly repeated by the remaining members of the system with the exception of the thrust link F which will move substantially in the direction of its length. In addition, the reduction in 20 the distance between the rear ends of the radial link H and jib tail-portion B will bear a definite ratio to the lift of the upper extremity of the jib head-portion A. Furthermore, the said rear ends 25 will always be contained in a vertical plane.

Proceeding from the foregoing and referring 30 now to Fig. 2 let the radial link H be removed from the thrust link F and the pivot G at the rear end of this latter be mounted on the crane frame. Then re-attach the radial link H pivotally 35 to the jib A, B at its pivot point C (which is not now mounted on the crane frame and is free to move) and pivot its upper end on a fixed point J on the frame (not shown) vertically above the rear ends of the thrust link F and jib tail-portion B. Angular motion of the radial link H about point J now causes the upper end of the arm D to move rearwards where before a similar movement forwards of its lower end would have been produced (see chain-dotted lines in Fig. 2). However, the reduction in the distance between the rear ends of the thrust link F and tail-portion B 40 still bears a definite ratio to the lift of the upper end of the jib head-portion A, the numerical value of this ratio depending on the relation between the lengths of the head and tail portions, A and B, respectively, of the jib. It should be noted, however, that the rear end of the tail-portion B is now always contained in the same 45 vertical plane.

If the thrust link F and the radial link H in the last arrangement are each extended beyond the pivots E and C respectively (see Fig. 3) they meet at K vertically beneath a point L on the jib head-portion A which is horizontally opposite to the fixed pivot J for the radial link H, the meeting point K also being located horizontally opposite to the rear end of the jib tail portion B. This applies whatever the position of the jib (see the alternative position of the parts shown in chain-dotted lines in Fig. 3) so that it follows that the point L of the head-portion A moves in a horizontal path.

It will now be seen that if it be arranged for the centre of gravity of the jib A, B to be located at the point L of the head-portion A the jib will be in balance for any position of this point along its horizontal path of travel and, further, that if hoisting rope pulls acting vertically on the jib at its forward and rearward ends as indicated by the arrows M and N in Fig. 3 be arranged to have an equal moment about the said point they also will be balanced. Should the centre of gravity L be at the centre of length of the jib A, B a single part of the hoisting rope at the rear end would balance a single part of the same rope at the forward end. Similarly if the length of the jib forward of the centre of gravity L be three times the length of the remainder, three parts of rope will be required at the rear end to balance a single part at the forward end. This may be arranged by suitably reeving the ropes. It will be understood that the ratio between the length of the jib forward of the centre of gravity and the length of the remainder of the jib will equal the ratio between the number of parts of rope at the rear end of the jib and the number of parts of rope at the forward end. The examples given are merely illustrative.

Although a crane having its jib arranged and supported as so far described with reference to Figs. 2 and 3 would operate satisfactorily there would be certain practical disadvantages. For example, the radial link H being anchored on the crane frame at J and disposed as indicated above, the crane frame (not shown) must either pass through the jib, which must be bifurcated at its rear or lower end, or pass outside the jib, thereby requiring a bifurcated frame.

In order to avoid these disadvantages, the radial link H is replaced by its equivalent at a lower height, the length and disposition of this equivalent link O (Fig. 3) being as follows: Its upper end is pivoted on the crane frame at a point P lying on a line EJ joining the lower end E of the arm D secured to the jib A, B to the theoretically correct position J for the upper end of the radial link H, its lower end is pivoted at Q on the said arm D towards the upper end thereof, and its direction is such that were it extended beyond the pivot Q it would pass through the point K at which the radial and thrust links intersect when extended (see the dotted line QK). Although both links H and O are shown in Fig. 3 it will be understood that the link H is removed when the link O is fitted. Due to this modification, the crane frame may be shorter and not pass completely through the jib which may be braced on its upper side to increase its rigidity. It will be understood that AB only represents the jib which, in practice, has an appreciable transverse dimension.

The use of the shorter equivalent link O entails a slight departure from the theoretically accurate horizontal movement of the centre of gravity L of the jib A, B but, since the thrust link F does

not remain always in the same angular position in practice as it is not of infinite length, the use of the thrust link described introduces a second departure from theoretical accuracy which is of opposite effect to the previous one and the two almost completely cancel out.

It should not be overlooked that the thrust link may be replaced by a straight slide and the equivalent link by an arcuate guide of a radius equal to the length of the link, although links are preferred. It may be remarked that the true theoretical level path of the centre of gravity can be ensured by the use of the slide and guide in combination.

The diagram of Fig. 4 illustrates the construction developed in the diagram of Fig. 3 applied to a jib A, B of which the centre of gravity L is disposed centrally of its length, the jib being shown in three different positions indicated by full lines, broken lines and chain-dotted lines, respectively. When the jib A, B is luffed from its full line position to its broken line position its upper extremity R moves in a curved path and rises through a vertical distance h , its centre of gravity L moves horizontally and its lower extremity S moves vertically downwards also through a distance h . In the same way, when the jib is luffed from its full line position to its chain-dotted line position its upper extremity R rises vertically through a distance h' and its lower extremity S falls vertically through the same distance.

Since the centre of gravity L is central of the length of the jib A, B, a single part M of hoisting rope at the upper extremity will be balanced by a single part N of the same rope at its lower extremity. Rope pulleys (not indicated in Fig. 4) are provided at R and S to take the hoisting rope which has a load hook on the end of the part M and has its part N guided over a pulley (not shown) disposed substantially vertically beneath the jib-end S, preferably at G (as assumed in Fig. 4), to run at U to a winding drum V mounted on the crane frame (not shown).

It will be seen that during the luffing movement of the jib from its full line position to its broken line position a length h of the part N of the hoisting rope is allowed to run upwardly over the pulley at S under the pull of the load. It follows that the load hook T remains at the same level throughout the movement of the jib despite the rise h of the pulley at R. Similarly, the load hook remains at the same level during the luffing movement to the chain-dotted position because a length h' of the rope-part N is paid out by the fall of the pulley at S to compensate for the rise h' of the pulley at R. No operation of the winding drum V is required, therefore, during the luffing of the jib in order to keep the load hook T at the same level throughout. Nevertheless the winding drum may be operated as desired during luffing without affecting the automatic compensation of the position of the load hook although the latter would then rise or fall in accordance with the direction of rotation of the drum.

The substantially constant horizontal velocity of the load hook T which may be required during luffing is simply ensured by arranging luffing means such as a screw and nut (not indicated in Fig. 4) to displace the jib A, B so that its centre of gravity L moves horizontally at a constant speed. So that the crane frame may not be made too high, it is preferred not to cause the luffing means to act at the point L of the jib but to arrange them at a lower level corresponding to the attachment of the actuating screw at a point on

a line joining the centre of gravity L of the jib and the lower end E of the arm D attached to the latter. The point of attachment of the screw should be as near the centre of gravity L as is permitted by practical considerations so that the departure from the desired constant speed will be very small. Other forms of luffing gear may, however, be employed although it may then not be possible to ensure substantially constant horizontal velocity for the load hook.

It will of course be understood that the links O and F and arm D referred to above will normally be duplicated so that one set is disposed on each side of the crane frame. The hoisting gear, slewing gear and so on do not form part of the present invention but the level luffing crane described may naturally be constructed as a travelling crane adapted for slewing if desired.

An indication of a practical form of construction of a crane corresponding to the diagram of Fig. 4 is illustrated by Fig. 5. Here the crane frame is indicated at W as being mounted on a rotatable platform X which may be driven in any suitable manner for slewing the crane and may in turn be mounted on rails in a manner permitting of the cranes being displaced bodily. The parts of this crane which correspond to the elements of the diagram of Fig. 4 are indicated by the reference characters also used in that diagram. Additionally illustrated are a further pulley S' for guiding the hoisting rope (necessitated by the shape of the jib A, B) and luffing gear comprising a screw Y pivotally attached at Y' to the link O and engaged in a motor-driven nut Z which is pivotally mounted at Z' on the crane frame W.

This crane operates exactly as has been described in relation to the diagram of Fig. 4.

Figs. 6 and 7 illustrate diagrammatically two further crane constructions and, where possible, corresponding parts are again indicated by like reference characters.

The crane of Fig. 6 is arranged to have its centre of gravity L at a distance from the pulley S of one-quarter of the length of the jib A, B, suitable counter-weighting or loading with ballast being resorted to, as will be understood. By reason of this fact a single part M of the hoisting rope at the upper end R of the jib requires three parts of the same rope at the lower end S of the jib and this is ensured by suitably reeving the rope, as shown at N', before it passes at U to the drum V.

In this example, furthermore, the luffing gear is slightly modified in its disposition by pivotally attaching the screw Y to the crane frame at Y' and pivotally mounting the motor-driven nut Z on the jib A, B at a point Z' lying on a line joining the centre of gravity L to the pivot point E for the upper end of the link F.

The operation of this crane is substantially as already described above except that the pulley R rises vertically, during luffing, three times as far as the pulley S sinks. This is due to the proportions chosen for the jib and still provides the necessary compensation for the load hook due to there being three parts of rope N' each of which releases one-third of the total rope required.

Fig. 7 also shows a crane in which the centre of gravity L is at a distance from the pulley S equal to one quarter of the total length of the jib A, B. In this case, however, a further load hook T' is provided, it being secured to a pulley T² that is supported by two parts M', M² of a hoisting rope separate from that carrying the

load hook T. The part M' of this rope is secured at its upper end to the jib structure and continues around the pulley T² as the part M² which runs over a pulley R' located midway between the centre of gravity L and the pulley R. The hoisting rope associated with the load hook T runs from the pulley R over the pulleys S' and S and extends then as three parts N' of rope between the pulley S and the pulley mounted at G before continuing at U to the winding drum V. On the other hand, the hoisting rope associated with the load hook T' runs from the pulley R' to a pulley (not shown) arranged alongside the pulley S and extends then as three parts of rope between the said pulley and another one (also not shown) arranged alongside that mounted at G before continuing at U' to a second winding drum V'.

In this crane the single part M of the hoisting rope for hook T balances the three parts N' of this rope as in the crane of Fig. 6. In addition, as only one (M') of the parts M', M² of the hoisting rope for hook T' is wound, the three parts of this rope at the lower end of the jib balance the two parts M', M² which are at distance from the centre of gravity L equal to one-and-one-half times the distance of the pulley S from the centre of gravity.

It will be understood that the necessary compensation is provided for both load hooks T and T' during luffing of the jib by reason of this method of reeving the hoisting ropes.

Many other arrangements to suit special circumstances may be made but it is thought that the examples given will be sufficient to illustrate the invention.

What I claim is:

1. A level luffing jib crane comprising a supporting frame, a balanced jib, a hoisting pulley at the load-carrying end of the jib, a first counter-loading pulley at the end of the jib remote from the load, a pivot for the jib located between the said ends thereof, a second counter-loading pulley on the supporting frame substantially vertically beneath the first counter-loading pulley, a winding drum on the said frame, a hoisting rope passed over said hoisting pulley and over said first and second counter-loading pulleys and attached to the said winding drum, a first link equal in length to the distance between the jib-pivot and the first counter-loading pulley and engaged at one end with the said jib-pivot and pivotally attached at the other end to the said frame, a second link pivotally attached at one end to the said frame substantially vertically beneath the said first counter-loading pulley and pivotally attached at the other end to a point on the jib offset downwardly from the longitudinal axis of the jib by a distance approximately equal to the distance between the jib-pivot and the first counter-loading pulley, the said first and second links being disposed along lines meeting beneath the centre of gravity of the jib on the level of the first counter-loading pulley and the pivotal connection on the frame for the first link being vertically above the said first counter-loading pulley, and means for luffing the jib about its pivot and thereby displacing the said first and second links to ensure substantially horizontal movement of the centre of gravity of the jib and substantially vertical movement of the first counter-loading pulley.
2. A crane according to claim 1, wherein the first link is replaced by an equivalent link having its one end pivoted to the crane frame at a point

contained in a transverse plane that also contains both the point of attachment of the second link to the jib and the intersection of a horizontal plane passing through the centre of gravity of the jib and a transverse vertical plane containing the centre of the first counter-loading pulley, the other end of the equivalent link being pivoted to the jib at a point located in a plane containing both the point of attachment of the said second link to the jib and the point at which the first link, if present, would be attached to the jib.

3. A level luffing jib crane comprising a balanced jib, a hoisting pulley at the load-carrying end of the jib, a first counter-loading pulley at the end of the jib remote from the load, a supporting frame located between the ends of the jib adjacent to that end carrying the said first counter-loading pulley, a pivot for the jib arranged between its ends, a first link pivotally attached at one end to a point on the upper end of the frame and engaged at the other end with the jib-pivot, a second link pivotally attached at one end to the frame substantially vertically beneath the first counter-loading pulley and at the other end to the jib at a point offset from and below the longitudinal axis of the said jib, a second counter-loading pulley on the frame substantially vertically beneath the first counter-loading pulley, a winding drum on the frame, a hoisting rope passed over the hoisting pulley and over the said first and second counter-loading pulleys to the winding drum, and jib-luffing means for moving the jib about the point thereon at which the said second link is attached and thus displacing the jib-pivot about the point on the frame at which the said first link is attached to the latter, the said first and second links being disposed along lines that meet at the intersection of a transverse vertical plane containing the centre of gravity of the jib and a horizontal plane containing the axis of the first counter-loading pulley.

4. A level luffing jib crane as claimed in claim 3, wherein the jib-luffing means comprises luffing gear arranged to displace the centre of gravity of the jib horizontally at substantially constant speed.

5. A level luffing jib crane as claimed in claim 3, in which the jib-luffing means comprises screw and nut luffing gear adapted to displace the centre of gravity of the jib horizontally at substantially constant speed.

6. A level luffing jib crane comprising a supporting frame, a horizontal pivot at the upper end of the said frame, a lower horizontal pivot on the said frame displaced out of the vertical plane containing the axis of the first-mentioned pivot, a balanced jib, an integral part on the jib extending downwards from the longitudinal axis of the jib adjacent to the lower end thereof, a horizontal pivot on the lower end of the jib-part spaced from the intersection of the medial line of the said part with the said axis by a distance substantially equal to that between the said intersection and the lower end of the jib, a horizontal jib-pivot located on the said medial line, a first link extending between the pivot at the upper end of the frame and the said jib-pivot, a second link extending between the lower pivot on the said frame and the pivot on the said jib-part, the said first and second links being of such lengths and so disposed that the lower end of the jib is substantially vertically above the said lower pivot, that a line joining

the pivot on the jib-part to the pivot at the upper end of the frame, when produced, passes through the intersection of a horizontal plane containing the centre of gravity of the jib and a transverse vertical plane containing the lower end of the jib, and that the two links lie on lines which meet at the intersection of a transverse vertical plane containing the said centre of gravity and a horizontal plane containing the said lower end of the jib, a hoisting pulley at the load-carrying end of the jib, a first counter-loading pulley at the lower end of the jib, a second counter-loading pulley on the frame vertically beneath the said lower end of the jib, a winding drum on the said frame, a hoisting rope passed over the hoisting pulley and over the said first and second counter-loading pulleys to the winding drum, and luffing means connected between the jib and the frame for displacing the centre of gravity of the jib horizontally at substantially constant speed.

7. A crane as claimed in claim 6, in which the luffing means comprises screw and nut gear.

8. A crane as claimed in claim 6, in which the first and second links are duplicated and one set is arranged at each side of the supporting frame.

9. A crane as claimed in claim 6, in which the luffing means comprises screw and nut gear pivotally attached at one end to the frame and pivotally attached at the other end to the jib at a point located on a line joining the centre of gravity of the jib to the pivot on the jib-part.

10. A crane as claimed in claim 6, including a further hoisting pulley intermediate the ends of the jib, a second winding drum on the frame, duplicate first and second counter-loading pulleys on the lower end of the jib and on the frame, respectively, and a second hoisting rope passed over the said further hoisting pulley and over the said duplicate first and second counter-loading pulleys to the said second winding drum.

11. In a crane as claimed in claim 6, mounting the supporting frame slewably on a travelling base structure.

12. A level luffing jib crane comprising a supporting frame, a balanced jib, a hoisting pulley at the load-carrying end of the jib, a first counter-loading pulley at the end of the jib remote from the load, a pivot for the jib located between the said ends thereof, a second counter-loading pulley on the supporting frame substantially vertically beneath the first counter-loading pulley, a winding drum on the said frame, a hoisting rope passed over said hoisting pulley and over said first and second counter-loading pulleys and attached to the said winding drum, means mounting the jib-pivot on the said frame for arcuate movement about a point thereon, a rigid part on the jib extending at an angle downwards away from the longitudinal axis of the jib with its upper end in the neighbourhood of the jib-pivot and its lower end spaced from the said jib-pivot by approximately the distance between the latter and the first counter-loading pulley, means connecting the lower end of the said jib-part to the frame for movement substantially along a line joining the said lower end and the point on the frame about which the jib-pivot moves, and means for luffing the jib and thereby simultaneously producing displacement of both the jib-pivot and the lower end of the said jib-part so that the centre of gravity of the jib moves horizontally and the first counter-loading pulley moves vertically.
